UNITED STATES PATENT OFFICE.

GEORGE E. MAIER, OF LOS ANGELES, CALIFORNIA.

BOILER-FLUE CONSTRUCTION.

Application filed April 3, 1922. Serial No. 549,317.

To all whom it may concern:

Be it known that I, GEORGE E. MAIER, a citizen of the United States, residing at Los Angeles, in the county of Los Angeles 5 and State of California, have invented new and useful Improvements in Boiler-Flue Construction, of which the following is a specification.

My invention relates to boiler construction and more particularly in effecting a practically non-leakable joint for connecting boiler tubes to boiler end plates.

An object is to provide a tube and end plate joint so constructed as to withstand 15 internal or external pressure and that will not loosen from the effect of expansion and contraction in the parts caused by the heat of the boiler.

Another object is to provide the end plate 20 from the inside face with an inwardly tapering set of openings, said openings extending substantially to the center of the plate section, or approximately so. The opening is then tapered from the outside face to the 25 center, thereby making openings with tapered walls adapted to receive annular gaskets and tubes with the ends of the tubes tapered practically as the walls of the inside openings are tapered and of a size admitting of the inter-positioning of said 30 gasket; placing said gasket and tubes in the opening, thereafter flaring the tube end and beading the same to effect a joint between the end plates and flue tubes.

35 A further object is to provide a tube and end plate construction with the use of one piece tubes having weld-less tube ends especially adapted for marine boilers wherein weld-less joints are specified.

40 With the foregoing objects in view, together with such other objects and advantages as may subsequently appear, my invention resides in the parts and construction hereinafter described, claimed and illustrated in the accompanying drawings, in which:—

Figure 1 is a sectional view of the boiler end plate showing the gasket and tube partly in elevation and in section.

50 Fig. 2 is a perspective of a portion of the tube showing the reduced end.

Fig. 3 is a sectional perspective of the annular ring gasket.

55 Fig. 4 is a fragmentary sectional perspective of the end plate taken through one of the openings.

Fig. 5 is a sectional view showing a modified form of construction,

More specifically, 10 is a section of a boiler end plate provided with numerous 60 openings 11 designated by dotted lines shown in Fig. 4.

Referring to Fig. 4 starting at the inside face 12 of the end plate 10 opening 11 is tapered toward the outside face 13 and extends to an annular diametrical edge 14 between the inner face 12 and the outer face 13, said opening thus forming an annular tapered wall 15 between the inner space 12 and the outer space 13. The edge 16 of the 65 wall 15 on the inner face 12 is of an annular diameter larger than the annular edge 14; the opening 11 is then tapered from the outer face 13 to the edge 14 thus forming a second annular tapered wall 17 between the outer face 13 and the inner face 12 of which the edge 18 on the outer face 13 is enlarged in size over the annular edge 14 between the faces 12 and 13. The annular inwardly tapering walls 15 and 17 70 meeting at the edge 14 will throughout the remainder of the specification be designated by the numeral 19; in Figs. 2, 3 and 4 I have shown each part constituting the tube assembly in one joint to more clearly show 75 the details of construction.

The tube 20 is of a slightly smaller diameter than the diametrical edge 16 of the opening 19, said tube 20 is reduced to a straight annular diametrical surface 21 80 parallel to the surface of tube 20, conforming to a size somewhat smaller than the diametrical edge 14. From the surface 21 to the tube section 20 a portion is tapered to form an annular conical surface 22 substantially at an angle parallel to the tapered wall 15.

A ring gasket 23 is annular in shape, having annular walls 24 and 25 mating surfaces 21 and 22 of the tube 20, so it may be 100 slipped onto the reduced portion of the tube 20, whereupon surfaces 24 and 25 of the gasket 23 will tightly fit the annular walls 21 and 22 of the tube 20. Gasket 23 is provided with an annular flange 26, the purpose 105 of which is to abut against wall 12 so that in assembly said gasket will not lose its position in the opening 19.

In assembling the gasket 23, tube 20 and end plate 10 to form a tight joint for obviating leakage, gasket 23 placed on tube 20 110 said gasket 23 and tube 20 are slipped

in the opening 19 and jammed therein till the wall 25 of the gasket 23 fits the wall 15 of the plate 10. Maintaining the position, the outer end 27 of the tube 20 is flared outwardly thereby expanding annular wall 24 of the gasket against the wall 17 of the plate 10, the stock of metal left is curved to form a bead 28; further working of the bead causes an annular drawing action on the 5 tapering section of the tube 20 and gasket 23 to effect a tight tapering joint on approximately a major portion of the opening 19 from the inside wall 12 of the plate section 10 and a minor portion from the outside 10 wall 13 to the plate section 10. With this construction the tapered portion of the tube 15 will be in opposition one to the other maintaining a tight joint.

In the modified form of construction 20 shown in Fig. 5 the tapered portions are shorter from the inside face 12 to the edge 14 and the tapered portions are longer from the outside face 13 to the edge 14.

From the foregoing, it will be seen that 25 any expansion or contraction internal or external pressure acting on the joint will not tend to loosen said joint, whereby any leakage of the tube is reduced to a minimum.

Various changes may be made in the shape 30 and proportion coming within the scope of the appended claims.

I claim:—

1. In a boiler, end plates, gaskets and tubes, said end plates provided with a series 35 of openings, each opening in said plate having two annular tapering walls, one wall

tapering from one side of the plate to near the center of the plate section and the second wall of substantially the same taper as the first mentioned wall extending to near the 40 center of the plate section from the side opposite the first named side; each gasket of tubular section formed to fit the first mentioned tapering wall and the remainder of the gasket formed straight and extending 45 through said openings, each tube provided with a reduced end, said end formed with a taper to fit the taper in the gasket and a straight portion extending through said gasket; said straight portion of the gasket 50 and said straight of the tube extending through said opening in the end plate being expanded and the remaining end of said tube beaded over against the said second wall of said end plate so that the first mentioned 55 tapered sections are in opposition to the second mentioned tapered sections, thus forming a tight joint.

2. In a boiler, an end plate having a flue 60 end receiving opening, the wall of which tapers from the inner and outer faces of the plate toward the center thereof, and a tube having an inwardly converging end portion adapted to extend into and conform to the taper on the inner face of the end plate and having its end portion flared outwardly from its converging portion to conform to the taper leading from the outside face of the plate with its extremity beaded into engagement with the outer face of said end plate. 65

GEORGE E. MAIER.
